CAR ROOF

Filed Aug. 19, 1929

UNITED STATES PATENT OFFICE

ALFRED R. WILSON, OF DETROIT, MICHIGAN, ASSIGNOR TO HUTCHINS CAR ROOFING COMPANY, OF DETROIT, MICHIGAN, A CORPORATION OF DELAWARE

CAR ROOF

Application filed August 19, 1929. Serial No. 386,918.

This invention relates to car roofs and has particular reference to a car roof of the character in which metal roofing sheets are employed.

- 5 This invention numbers among its objects the provision of means for supporting the roofing sheets at the ridge of the car and for limiting movement of the roof sheets transversely of the car.
- 10 Other objects and advantages of the invention together with the numerous novel details of construction will become more apparent as the following description proceeds, particularly when reference is had to the accompanying drawing wherein,

Figure 1 is a fragmentary plan view of a car roof showing the invention applied to the same;

Figure 2 is a transverse sectional view 20 through a portion of the car roof shown in Figure 1;

Figure 3 is a fragmentary sectional view taken substantially on the line 3—3 of Figure 1;

25 Figure 4 is a fragmentary sectional view taken substantially on the line 4—4 of Figure 1;

Figure 5 is a fragmentary sectional view showing the connection of the roof sheets at 30 the eaves of the roof, and

Figure 6 is a fragmentary sectional view taken substantially on the line 6—6 of Figure 1.

In the drawing there is disclosed a car roof, 25 the supporting frame of which includes a ridge pole A, side plates B and a number of purlines C arranged between the ridge pole and side plates. In the type of roof disclosed, wooden sheathing D is shown as being 30 supported on the ridge pole, purlines and side plates, this sheathing forming a wooden roof for the car. It is to be understood, however, that the invention is not limited to this particular type of roof since the inventive principles involved will find equal utility in a car roof in which the metallic roofing sheets are self-supporting and are mounted directly on the roof frame.

35 In the construction disclosed roof sheets E are arranged on opposite sides of the ridge

pole, each sheet extending from the ridge of the car to one of the eaves thereof. These roof sheets are supported for movement relative to each other to compensate for weaving of the car roof during movement of the car, and accordingly each roof sheet is provided at its outer edge adjacent the eave of the car with a return bent flange F adapted to fit in a pocket formed by the reversely bent portion G of a flashing strip H which is secured in any desired manner to the fascia I which in turn is secured with the side sheathing J to the side plate B. Thus each roofing sheet is loosely held down at the eave of the car while provision is made for movement of the roofing sheet transversely of the car.

The roofing sheets are positioned between mullions K arranged in spaced relation upon the roofing boards D and secured thereto. At their opposite sides the roofing sheets are provided with flanges L terminating in inwardly and downwardly extending portions M, these portions being spaced from the sides of the mullion strips as illustrated in Figure 3. Forming the joint between the sides of adjacent sheets and covering the mullions, are joint caps N which have downwardly extending side flanges which embrace the flanges L but are spaced therefrom to permit lateral movement of the roofing sheets. The transverse caps N may be anchored at their outer ends by engagement in the pocket formed by the reversely bent portion of the flashing strip H as clearly illustrated in Figure 2 of the drawing.

40 Adjacent the ridge pole each roofing sheet is provided with a marginal portion bent to form an inverted channel. Thus as clearly illustrated in Figure 4 of the drawing, each roof sheet adjacent the ridge pole is bent upwardly as at O and then forwardly and downwardly to provide an inverted channel shaped marginal portion which may be engaged with the channel shaped marginal portion of the corresponding sheet on the opposite side of the ridge pole in the manner illustrated. Thus corresponding sheets on opposite sides of the ridge pole are detachably connected to each other at the ridge pole, the marginal channel shaped portion of one roof

sheet embracing the marginal channel shaped portion of the other roof sheet. Forming the joint between adjacent roof sheets at the ridge of the car are ridge caps

6 P, each ridge cap extending between spaced mullions as clearly illustrated in Figure 1 of the drawing.

At the juncture of every four roof sheets at the ridge of the car, center caps Q are provided, these center caps embracing adjacent ridge caps and adjacent transverse caps in the manner clearly illustrated in Figures 1 and 2 of the drawing and these caps form supports for a running-board saddle R which 10 in turn supports the usual running-board S. Bolts T extend through the running-board saddle and the center caps and are anchored in the ridge pole for holding the center caps and running-board saddle in position.

15 20 For supporting the marginal portions of the roof sheets adjacent the ridge pole and for limiting transverse movement of the roof sheets, members U are provided, each member U comprising a short section of an inverted channel bar which is anchored to the ridge pole by the bolt T. Each member U extends between the adjacent ends of aligned mullions and projects into the channel formed by the inverted channel portions of 25 adjacent roof sheets. Thus as clearly illustrated in Figure 1 of the drawing, opposite ends of the member U extend into the channels formed by the marginal portions of the four adjacent roof sheets. The member U

30 35 is of slightly less cross section than the channel portions of the roof sheets to permit a slight movement of the roof sheets transversely of the car roof but being fixed to the ridge pole limits movement of the roof sheets 40 transversely of the car roof.

From the above it is believed that the invention will be clearly apparent. The roof sheets are loosely supported whereby they may yield to compensate for the weaving of 45 the car roof. At the juncture of four adjacent roof sheets at the ridge of the car, the members U are provided and these members by engaging the under sides of the marginal channel shaped portions of the adjacent roof 50 sheets, support these portions of the roof sheets at the ridge of the car and also by engaging the sides of the channel shaped portions of the roof sheets, limit transverse movement of the roof sheets. By arranging 55 the member U in the manner disclosed, one member U will support four roof sheets and will limit transverse movement of all four of these roof sheets, thus reducing to a minimum the cost and labor incident to the 60 installation of these members.

While the invention has been described with considerable detail it is to be clearly understood that the description is for the purposes of illustration only and is not definitive of the limits of the inventive idea.

The right is therefore reserved to make such changes in the details of construction and arrangements of parts as will fall within the purview of the attached claims.

What I claim as my invention is:

1. In a flexible car roof, a roof sheet extending from the ridge of the car to one of the eaves thereof, and member fixedly mounted at the ridge of the car for supporting the roof sheet, while providing for a limited movement of the roof sheet transversely of the car at the ridge thereof. 70

2. In a flexible car roof, a ridge pole, a roof sheet extending from the said ridge pole to one of the eaves of the car, said roof sheet being provided with an inverted channel shaped marginal portion adjacent the said ridge pole, and means fixed to said ridge pole and extending into the channel portion of said roof sheet in engagement with the base of the channel portion of said roof sheet but in spaced relation to the sides thereof for supporting the adjacent portion of the roof sheet and for limiting movement of said roof sheet transversely of said car. 80

3. In a flexible car roof, a ridge pole, roof sheets arranged on opposite sides of said ridge pole, and a member fixed to said ridge pole and engaging the marginal portions of adjacent roof sheets for supporting said roof sheets adjacent said ridge pole, said member having portions normally spaced from portions of said roof sheets adapted to limit transverse movement of said roof sheets. 85

4. In a flexible car roof, a ridge pole, roof sheets arranged on opposite sides of said ridge pole, each of said roof sheets being provided with an inverted channel shaped marginal portion adjacent said ridge pole, the channel shaped marginal portions of the roof sheets on one side of said ridge pole being embraced by the channel shaped marginal portions of the corresponding roof sheets on the opposite side of said ridge pole, and a member fixed to said ridge pole at the juncture of four of said roof sheets and engaging the bases of the channel shaped portions of said roof sheets for supporting said roof sheets, said member having side portions spaced from the sides of the channel shaped marginal portions of the roof sheets adapted to limit movement of the roof sheets transversely of the car. 100

5. In a flexible car roof, a ridge pole, roofing sheets arranged on opposite sides of said ridge pole, corresponding roof sheets on opposite sides of said ridge pole having inter-engaging marginal portions adjacent said ridge pole, and an inverted channel shaped member fixed to said ridge pole and engaging the inter-engaged marginal portions of said roof sheets for supporting said roof sheets, said member being of less cross sectional width than the marginal portions of said roof sheets to provide for movement of said roof sheets. 110 115 120 125 130

transversely of the car at the ridge thereof.

6. In a flexible car roof, a ridge pole, an inverted channel bar fixed to said ridge pole and extending longitudinally thereof, a roof sheet arranged on one side of said ridge pole and having an inverted channel shaped marginal portion loosely embracing said channel bar, and a second roof sheet arranged on the other side of said ridge pole and having an inverted channel shaped marginal portion embracing the channel shaped marginal portion of said first mentioned roof sheet.

7. In a flexible car roof, a ridge pole, a roof sheet extending from the said ridge pole to one of the eaves of the car, said roof sheet being provided with an inverted channel shaped marginal portion adjacent the said ridge pole, and an inverted channel shaped member fixed to said ridge pole and arranged within the inverted channel shaped marginal portion of the roof sheet, the base of said inverted channel shaped member engaging the base of the channel shaped marginal portion of said roof sheet to support the roof sheet and the sides of said channel shaped member being spaced from the sides of the channel shaped marginal portion of the roof sheet and constituting stops for limiting movement of the roof sheet transversely of the car.

8. In a flexible car roof, roof sheets extending from the ridge of the car to the eaves thereof, and a member fixedly mounted at the ridge of the car and engaging the marginal portions of adjacent roof sheets for supporting said roof sheets, said member having portions normally spaced from portions of said roof sheets and arranged to limit transverse movement of said roof sheets.

9. In a flexible car roof, roof sheets arranged on opposite sides of the ridge of the car, corresponding roof sheets on opposite sides of the ridge having interengaging marginal portions adjacent the ridge of the car, and an inverted channel shaped member fixedly mounted at the ridge of the car and engaging the interengaging marginal portions of said roof sheets for supporting the latter, said member being of less cross sectional width than the marginal portions of said roof sheets to provide for limited movement of said roof sheets transversely of the car at the ridge thereof.

10. In a flexible car roof, an inverted channel bar fixedly mounted at the ridge of the car and extending longitudinally thereof, and a roof sheet arranged on one side of the ridge of the car and having an inverted channel shaped marginal portion loosely embracing said channel bar.

60 In testimony whereof I affix my signature.
ALFRED R. WILSON.
